UNITED STATES PATENT OFFICE.

WILLIAM S. BLAZER, OF INDIANAPOLIS, INDIANA.

HAIR RECEIVER.

Application filed April 23, 1924. Serial No. 708,525.

To all whom it may concern:

Be it known that WILLIAM S. BLAZER, a citizen of the United States, residing at Indianapolis, in the county of Marion and State of Indiana, has invented new and useful Improvements in Hair Receivers, of which the following is a specification.

In placing combings of hair in receivers now in use, it is difficult to remove the hair

from the fingers. The hair is, as a rule, removed from the comb and wrapped around the finger. The person then inserts the finger in the receiver and endeavors to push the wrapped hair from around the finger and at the same time endeavors to retain it in the receiver. Very often several attempts are necessary in order to cause the hair to remain in the receiver. Furthermore, the receivers now in use are relatively light in weight and in removing the hair from the finger the receiver is pushed around over the dresser, causing a disarrangement of the covering on the dresser and sometimes causing the receiver to be pushed too far to the edge of the dresser, resulting in its falling to the floor.

It is the purpose of the present invention to provide a hair receiver to overcome these difficulties and to accomplish this result, the present hair receiver includes a circular brush in the top of the receiver which acts to brush the hair off the finger when inserted therethrough so that the hair will remain in the interior of the receiver.

Another purpose is to provide a base of relatively heavy material on which the upper or cylindrical wall of the receiver is fastened so as to act to retain the receiver in position on the dresser.

A further purpose is to provide means for connecting the upper part or cylindrical wall of the receiver and the base, whereby the two may be easily and very quickly separated when it is desired to remove the quantity of hair from the receiver.

A still further purpose is the provision of means for retaining a circular ring (which carries the hair bristles) in an annular rabbet adjacent an opening in the top of the receiver. In fact, it is the purpose to retain the ring in position in such wise as to permit the same to be easily removed for cleaning the hair bristles.

It is to be understood that the particulars herein given are in no way limitative and

that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in perspective of the improved hair receiver constructed in accordance with the invention.

Figure 2 is a sectional view on line 2—2 of Figure 1, showing the connection between the cylindrical wall of the receiver and the base, as well as showing the connection between the hair carrying ring and the top of the receiver.

Figure 3 is an enlarged detail view of a portion of the top of the receiver and a portion of the ring, clearly showing the means for connecting the ring to the annular rabbet.

Referring to the drawings, 1 designates the base of the receiver which may be constructed of any suitable material, either celluloid, ivory, glass, amber, china or any other material. This base may have an interior core of heavier material, for instance, as shown at 2. It is possible to construct the base of metal. However, if constructed of celluloid or similar material, a metal disk, as indicated at 2, may be embedded in the under face of the base.

The base has an upstanding cylindrical flange 3 which, in the present instance, is interiorly threaded, as at 4, and 5 denotes the cylindrical wall of the receiver, the exterior of which, adjacent its lower edge, has threads to engage the threads 4, thereby connecting the wall of the receiver with the flange of the base. It is obvious that the wall of the receiver may be cylindrical or otherwise shaped or may be provided with any suitable ornamentation or colored.

The wall 5 is made integral with the top 6 which has a central opening 7 through which the hair on the person's finger may be inserted. The top 6 on its under face has a downwardly extending flange 8 in surrounding relation to the opening 7. The top adjacent to and concentric with the opening 7 has an annular rabbet 9 which receives a ring 10.

The wall of the rabbet is provided with

diametrically opposite lugs 11 which engage with bayonet slots 12 formed in the exterior cylindrical surface of the ring. The ring is inserted in the rabbet so that

5 the lugs will enter the bayonet slots and by imparting a partial turn to the ring, the lugs 11 may enter the offsets 13 of the bayonet slots, thereby holding the ring securely in the rabbet.

10 While lug and bayonet slot connections are at present employed, it is obvious that any other suitable connection may be used. In fact, the ring may be threaded in the rabbet in the same manner as the 15 receiver is connected to the base. It is obvious that the base may be connected to the receiver by a lug and bayonet slot instead of threads or other connection used.

The ring 10 on its inner cylindrical surface is provided with hair bristles 14 which extend radially inwardly and downwardly. These bristles terminate a short distance from the center of the ring so as to cause an opening to be formed through the 25 bristles so that a finger may be easily inserted. The hair from the comb is first wrapped in a wad on the finger or otherwise made into a wad and is then inserted through the opening of the hair bristles. 30 The bristles act as means to cause a ready removal of the hair from the finger as the finger is withdrawn.

In using the old style receivers, it is necessary to insert the finger several times in 35 the receiver in order to cause the hair to be removed from the finger. With the present device it is only necessary to insert the finger once through the opening of the hair bristles for the reason that the bristles will 40 readily brush the hair from the finger and retain it on the interior of the receiver. It is possible that some of the hair may adhere to the bristles but as each wad is inserted,

the successive wads act to remove the wads previously inserted.

The invention having been set forth, what is claimed is:

1. A hair receiver comprising a casing having a rabbeted opening in its top, and a circular brush with an opening therethrough engaged in said rabbet, the bristles of the brush extending inwardly and downwardly and acting to brush the hair from the finger as it is inserted.

2. A hair receiver comprising a casing 55 provided with an opening in its top, the under face of the top having a rabbet, a circular brush including a holder and inwardly and downwardly extending bristles, and means for securing the holder in the rabbet, whereby the bristles may act to brush the hair from the finger as it is inserted.

3. A hair receiver comprising a casing, a circular brush carried by the top thereof, 65 the brush having a central opening and provided with downwardly and inwardly extending bristles to brush the hair from the finger as it is inserted, said casing comprising a base and a cylindrical wall, and 70 means for connecting the cylindrical wall to the base.

4. A hair receiver comprising a casing, a circular brush carried by the top thereof, the brush having a central opening and provided with downwardly and inwardly extending bristles to brush the hair from the finger as it is inserted, said casing comprising a base and a cylindrical wall, and 80 means for connecting the cylindrical wall to the base, said base being weighted so as to retain the receiver in position on a flat surface.

In testimony whereof he affixes his signature.

WILLIAM S. BLAZER.
